UNITED STATES PATENT OFFICE.

WILLIAM THORNLEY, OF MARRICKVILLE, NEW SOUTH WALES, ASSIGNOR
TO HENRY JUTSON FISHER, OF BIRMINGHAM, ENGLAND.

LAMP OR LANTERN.

SPECIFICATION forming part of Letters Patent No. 588,506, dated August 17, 1897.

Application filed November 14, 1896. Serial No. 612,136. (No model.) Patented in New South Wales October 20, 1893, No. 4,687; in Victoria November 6, 1893, No. 10,944; in New Zealand January 18, 1894, No. 6,583; in England May 8, 1895, No. 9,152; in South Australia November 11, 1895, No. 3,310, and in Queensland January 21, 1896, No. 3,053.

To all whom it may concern:

Be it known that I, WILLIAM THORNLEY, a subject of the Queen of Great Britain, residing at Marrickville, in the Colony of New

5 South Wales, have invented certain Improvements in Oil Lamps or Lanterns, (for which I have obtained a patent in Great Britain, No. 9,152, bearing date May 8, 1895; in New South Wales October 20, 1893, No. 4,687; in 10 South Australia November 11, 1895, No. 3,310; in Victoria November 6, 1893, No. 10,944; in New Zealand January 18, 1894, No. 6,583, and in Queensland January 21, 1896, No. 3,053,) of which the following is a specification.

15 My invention relates to improvements in oil lamps and lanterns, and has special reference to those in which kerosene or other mineral oils are burned and which do not necessitate the use of a chimney.

20 The object of my invention is to construct and fit a lamp and its parts in such a manner that the flame cannot under ordinary usage be extinguished when the lamp is subjected to a jolting, swinging, or shaking movement, 25 or to any combination of these.

Furthermore, my invention is such that a better system of air-supply to the burner is effected, which materially supports combustion and adds to the lighting power of the 30 said lamp.

My invention is particularly adapted to the well-known Batton burner; and it consists in the novel construction, arrangement, and combination of parts hereinafter described, 35 and particularly pointed out in the claims following the description.

To practically illustrate my invention and also the manner in which the same is carried into effect, the accompanying sheet of drawings represents, in—

40 Figure 1, a hand lamp or lantern constructed according to my invention. This view illustrates the lower portion of the lamp in section, showing clearly the air-supply passage or tube, the air-chamber surrounding the burner proper, into which the air-supply passage is directed, and also the coincident slot or piercing within the bottom of the body of the lamp. Fig. 2 illustrates a section of

the burner separated from the lamp-body, 50 while Figs. 3, 4, and 5 show, respectively, a side view, a top side plan, and an under side plan of Fig. 2.

The burner part *a*, with its oil container or reservoir *b*, is fitted within the body *c*² of the 55 lamp *c* and is provided with a burner proper, *a*², of the well-known Batton construction and means for raising and lowering the wick. Surrounding the middle part *a*³ of the burner proper, *a*², and fixedly connected to the top of 60 the oil-container *b* is a circular air-chamber *d*, open at its top end *d*² and having provided at a suitable point in its lower part an opening or piercing *d*³, constituting an entrance to the said air-chamber *d* from an air passage 65 or tube *d*⁴, arranged down the side of the oil-container *d* and whose lower end *d*⁵ is open and arranged to come coincident with a hole or piercing *e*, formed within the bottom of the body of the lamp. 70

The metal of the walls of the air-chamber *d*, adjacent to the opening *d*³, as before described, depends downward at *d*⁶ into the top part of the air-supply passage or tube *d*⁴ and constitutes a baffle-plate to prevent the in-rush of air to the air-chamber becoming too great and also forms a means for diffusing the same around the inside walls of the air-chamber *d*. The metal at the top edge of the 75 said air-chamber *d* is turned circumferentially inward at *f* to direct in some degree the air-supply to the flame from the passage *d*⁴. 80

The air which enters at the piercing *e* and passes up the air-supply passage or tube *d*⁴ is dispersed or diffused by means of the baffle-plate *d*⁶ and caused to pass upward between and around the middle part *a*³ of the burner proper and the inner face of the walls of the air-chamber *d* to the flame, which effectively prevents a slight vacuum being caused momentarily around the said flame and the light being extinguished when the lamp is subjected to a shaking or jolting movement. I wish it to be understood that the proportions of the said air-chamber *d* and also its 90 supply-passages may be varied according to the power of the light and, if necessary, the 95 said air-passages may be duplicated, always

providing that no direct draft is caused to enter the air-chamber.

My improvements are applicable to all kinds of lamps and lanterns used upon road-
5 vehicles and railroads and also carried by the hand, and are designed for the purpose of over-
coming the difficulty experienced in prevent-
ing the same from being extinguished when moved about, jolted, or waved.

10 Having now fully described my invention, what I claim, and desire to secure by Letters Patent, is—

15 1. In a lamp, the combination with the oil-
container b and the burner proper a^2 , of an
annular air-chamber d arranged on the oil-
container and surrounding the burner, said
chamber being open at its top and terminat-
ing at a point beneath the burner and pro-
vided at its lower end and at one side with an
air-inlet d^3 , a vertical supply-tube d^4 arranged
20 on one side of the oil-container and connected
at its upper end with the inlet d^3 and at its
lower end with an inlet e formed in the base
of the lamp, and a depending baffle-plate d^6
25 above the inlet d^3 and between the upper end

of the tube d^4 and the interior of the air-
chamber, substantially as described.

2. In a lamp, the combination with the oil-
chamber b and the burner proper a^2 , of an
annular air-chamber d arranged on the oil-
30 container and surrounding the burner, said
chamber being open at its top and terminat-
ing at its upper end in an inwardly-turned
flange f below the burner, said chamber be-
ing provided at its lower end and at one side 35
with an air-inlet d^3 , a vertical supply-tube d^4
arranged on one side of the oil-container and
connected at its upper end with the inlet d^3
and at its lower end with an inlet e formed in
the base of the lamp, and a depending baffle-
40 plate d^6 above the inlet d^3 and between the
upper end of the tube d^4 and the interior of
the air-chamber, substantially as described.

In testimony whereof I have signed my
name to this specification in the presence of 45
two subscribing witnesses.

WILLIAM THORNLEY.
